TIME-INDICATING FACE FOR A HOROLOGE

Shigeru Fukumoto, Nishinomiya, Japan, assignor to
Kabushiki Kaisha Suncrux Research Office, Higa-
shinada-ku, Kobe, Japan

Filed Oct. 13, 1971, Ser. No. 189,054

Claims priority, application Japan Apr. 15, 1971

Term of patent 14 years

Int. Cl. D10—07

U.S. Cl. D42—1 B

FIG. 1 is a front elevational view of a time-indicating face for a horologe showing my new design, the rear being substantially identical thereto;

FIG. 2 is a side elevational view thereof; and

FIG. 3 is an edge elevational view thereof.

The drawings are shaded for color contrast.

I claim:

The ornamental design for a time-indicating face for a horologe, as shown and described.
